UNITED STATES PATENT OFFICE.

JEROME REDDING, OF MALDEN, ASSIGNOR TO HIMSELF AND HARVEY REDDING, OF EVERETT, MASSACHUSETTS.

ELECTRICAL GAS-BURNER.

SPECIFICATION forming part of Letters Patent No. 252,848, dated January 24, 1882.

Application filed August 18, 1881. (Model.)

To all whom it may concern:

Be it known that I, JEROME REDDING, of Malden, in the county of Middlesex and State of Massachusetts, have invented certain Improvements in Electrical Gas-Burners, of which the following is a specification.

This invention relates to that class of electrical gas-burners which are composed in part of a tube or section of insulating material—such as porcelain or glass—attached to the gas-pipe and supporting the burner-tip, and provided with electrodes for lighting the gas-jet by induced currents of electricity.

The chief object of the invention is to enable a common lava tip to be inserted in and removed from the insulating section without disturbing the connection of the electrodes thereto, thereby enabling any desired tip to be applied to the section, and enabling one tip to be changed for another adapted to give a different form to the flame.

The invention also has for its object to provide improved means for securing the electrodes to the insulating section, and to adapt the latter for the reception of the electrodes.

To these ends my invention consists in the several improvements which I will now proceed to describe and claim.

Of the accompanying drawings, forming part of this specification, Figure 1 represents a side elevation of a gas-burner embodying my invention. Fig. 2 represents a top view of the same. Fig. 3 represents a section on line *x x*, Fig. 2. Fig. 4 represents a side elevation of the insulating section and its electrodes before the application of the lava tip. Fig. 5 represents a longitudinal section of the same. Fig. 6 represents a section on line *y y*, Fig. 5. Fig. 7 represents a longitudinal section of the insulating section without the electrodes. Fig. 8 represents a section on line *z z*, Fig. 7.

The same letters relate to the same parts in all the figures.

In the drawings, *a* represents the insulating section or tube of a gas-burner of the class above described, the same being composed of porcelain or other suitable material.

In carrying out my invention I form in the upper end of the section *a*, a socket, *b*, formed to receive and fit closely the tapered lava tip *c*;

and outside of the socket *I* affix to the section *a* the electrodes *d d*, the latter being so secured that the tip can be applied and removed without disturbing the connection of the electrodes to the section *a*. I secure the electrodes 55 to the section by means of a suitable water-proof yielding material, which also forms the socket *b*, the electrodes being embedded in said material, and the latter molded or formed to present a smooth yielding inner surface, 60 adapted to accurately fit the tip and permit the latter to be readily removed. The best material of which I am aware for this purpose is asbestos paper saturated with linseed-oil, and when this is used I prefer to form longitudinal slots or recesses *e e* in the interior of the upper end of the section *a*, said end being preferably tapered to correspond to the taper of the tip *c*, but of larger diameter. The paper is wrapped around the portions of the electrodes which are to be embedded, and the electrodes so inclosed are placed in the slots *e e*, 65 after which a collar or tube of the paper is placed in the tapered portion of the interior of the section *a* and pressed closely against said portion, so that it forms the socket *b*. The socket thus formed is of a slightly yielding nature, so that when the tip is pressed into its place the leakage of gas between the tip and socket will be prevented. This material, being both water-proof and a non-conductor of 70 electricity, not only insulates the electrodes, but also prevents any moisture which may be in or upon the material of the section *a* from conducting the electric current from one electrode to the other through the section *a*, and so interfering with the lighting of the gas by preventing the passage of a spark between the slightly separated ends of the electrodes at the orifice of the tip.

It will be observed that by adapting the section *a* to hold a lava tip and permit it to be removed and replaced by any other without disturbing the connection of the electrodes, I enable the section *a* to be sold as an article of 95 manufacture and used with a tip having any desired form of gas - orifice, and that in case a change is desired in the form of the flame after the burner has been applied it can be effected by simply substituting a new tip 100.

for the original one without requiring the removal of the section *a*. Heretofore in gas-burners of this class the section *a* and the tip have been rigidly connected, so that they could not be separated excepting with much difficulty and risk of breakage.

Having thus described my invention, I claim—

1. As an article of manufacture, an insulating section for gas-burners, having a yielding socket, substantially such as herein described, adapted to receive and permit the removal of a common lava tip, and electrodes secured to said section outside of the socket, as set forth.
2. The combination of the insulating section, having a yielding socket adapted to receive and permit the removal of a common lava tip, and electrodes secured to said section outside

of the socket by a water-proof cement, substantially such as described, in which said electrodes are embedded, substantially as and for the purpose described.

3. The improved molded insulating section or tube for a gas-burner, having slots or grooves made on its inner surface at its upper end for the reception of the electrodes and the cement or material whereby said electrodes are secured, as set forth.

In testimony whereof I have signed my name to this specification, in the presence of two subscribing witnesses, this 16th day of August, A. D. 1881.

JEROME REDDING.
